MEANS FOR ATTACHING TILE FACINGS TO WALLS

Filed Nov. 9, 1931

UNITED STATES PATENT OFFICE

HENRY BARTELS, OF CHICAGO, ILLINOIS

MEANS FOR ATTACHING TILE FACINGS TO WALLS

Application filed November 9, 1931. Serial No. 573,842.

This invention relates in general to wall facings, but particularly to an improved means whereby a tile facing can be secured to a wall which has already been plastered or finished.

Heretofore when it has been desired to set tile in a wall that has previously been finished, it has been necessary to "tear out" or remove the old plaster and laths, with its attendant dust and dirt, and then nail or secure metal laths or sheets of expanded material to the wall supporting structure, after which the various coats of plaster are built up and the tile applied or set. This method also requires considerable time and is somewhat expensive.

It is one of the objects of the present invention to apply tile to a wall which has already been constructed, without necessitating chopping away or removing any portion of the wall or surface.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a perspective view of a portion of a wall structure showing the manner of securing tiles thereto according to the principles of this invention, and with portions in elevation, portions in section and portions broken away.

Figure 2 is a vertical, sectional view of one portion of the wall, taken on line 2-2, Figure 1.

Figure 3 is a vertical, sectional view of another portion of the wall, taken on line 3-3, Figure 1.

Figure 4 is an elevation of a portion of the reinforcing and supporting net work.

Referring more particularly to the drawing the numeral 10 designates generally the usual studding, and 11 the laths of a wall construction to which the usual coating of plaster 12 is applied, and which coating forms the finished wall structure of a build-

ing. This coating 12 is applied in the usual manner and in instances where the wall has been provided with a finish coating so as to render the same non-porous or waterproof, the tile may be secured thereto without the application of any further coating on the wall. In instances where the wall surface is finished in the rough and is quite porous, a coating of shellac or other material may be applied thereto to fill up the pores and render the same moisture-proof. If desired, however, a sheet of suitable paper or other material may be applied to the wall over the surface adjacent which the tile is to be secured so as to render the wall impervious to moisture.

However, in many buildings where it is desired to make use of the present invention, the walls have generally been finished either by a coating of paint, calcimine, or other material, and in such instances the present invention may be applied without applying any further coating to the wall.

In carrying this invention into operation there is provided a grille work, preferably in the form of wire constructed of vertical wires 13 and horizontal wires 14 intersecting each other and spaced from each other for any desired distance to form any desired size of mesh 15. These wires 13 and 14 may be of any desired diameter, but are preferably of a small diameter and the wires are of sufficient stoutness so that they will maintain their shape, but are pliable to an extent to permit the wires to be bent as shown in Figure 1, to form angles 16-17 to fit into corners 18 in the wall structure and 19 at the base of the wall, where the wall abuts the floor, or to form angles 20 to be bent around corners 21 formed in the wall structure.

The upright wires 13 are of a sufficient length preferably to terminate adjacent the top of the tile to be applied and adjacent the floor 22 as shown at 23 in Figure 1, or they may be of a length that the lower end 24 thereof may be deflected laterally to project over the floor.

The horizontal wires 14 are preferably arranged on the front face of the uprights 13, that is on the face of the upright wires oppo-

site to the face which stands adjacent the wall 12 and secured to the rear face of the grille work are horizontal wires 25 arranged intermediate the horizontal wires 14.

The wires 25 are of a diameter considerably greater than the diameter of the horizontal wires 14 so that when the grille work is placed against the face of the wall 12, the wires 25 will rest against the surface of the wall as shown in Figures 2 and 3, to hold the grille work spaced from the face of the wall 12, and the whole structure is secured in position by means of suitable fastening devices 26 in the form of staples which pass over the horizontal wires 25 and enter the studs 10 or the laths 11.

Any number of these fastening devices 26 may be employed and the wires 25 are preferably of a length to extend across the space between adjacent studs 10.

The wires 25 are preferably constructed in predetermined lengths and the proximate ends of the adjacent wires 25 are spaced from each other as at 27, so as not to interfere with the bending of the wires 14 or, if desired, the wires 25 may be continuous and if continuous may be bent to form angles 28 adapted to enter the corners of adjacent walls.

The grille work thus formed is secured in position against the wall by simply placing the grille work against the wall and inserting the fastening devices 26. The wires 25 being of a predetermined diameter, will hold the grille work spaced from the face of the wall to provide a suitable space for the plaster 29 behind the grille work. The plaster or plastic material 29 is applied to the wall 12 in the ordinary and usual manner preferably by means of a trowel or other suitable device and is of a sufficient thickness to entirely cover the grille work including the rods 25 of the larger diameter, and any suitable thickness of plastic material may be applied. The tiles 30 are then applied to the face of this plastic material 29 and set or "pounded" down in a manner well known in this art.

The rods 25 also serve the purpose of preventing the plastic material from settling down or "sliding" behind the grille work.

It will be manifest that with this invention a tile facing may be readily applied to a wall which has previously been completed, expeditiously and without necessitating "chopping out" or removing any of the previously completed wall and by reason of the fact that the plastic material 29 will be held from "settling down" or "sliding" behind the tile, the wall surface 12 even though it may settle and form cracks behind the tile facing, will be concealed from view and the tile will not be affected thereby.

While the preferred form of the invention has been herein shown and described, it is to be understood that various changes may be made in the details of construction and in the

combination and arrangement of the several parts, within the scope of the claims, without departing from the spirit of this invention.

What is claimed as new is:

1. A tile facing for plaster walls comprising a section of grille work disposed directly adjacent the surface of a wall and in spaced relation thereto, fastening means for securing the grille work in position, plastic material contacting the surface of the wall and embedding said grille work, and tiles secured in position by said plastic material and covering said grille work, said grille work embodying spaced horizontal and upright rods arranged in intersecting planes, some of said horizontal rods being of a greater diameter than others of the horizontal rods and abutting the wall surface to hold the remaining portion of the grille work spaced from the wall and operating to maintain the plastic material against sagging.

2. A tile facing for plastic walls comprising a section of grille work disposed directly adjacent the surface of a wall and in spaced relation thereto, fastening means for securing the grill work in position, plastic material contacting the surface of the wall and embedding said grille work, and tiles secured in position by said plastic material and covering said grille work, said grille work embodying spaced horizontal and upright rods arranged in intersecting planes, some of said horizontal rods being of a greater diameter than others of the horizontal rods and abutting the wall surface to hold the remaining portion of the grille work spaced from the wall, and also serving to prevent the said plastic material from settling down behind the grill work and tile.

3. A tile facing for plaster walls comprising an apertured supporting and reinforcing structure, disposed adjacent the surface of the wall, means carried by said reinforcing structure for holding said structure spaced from the wall, said means embodying an element secured to, projecting from and extending along the rear face of said structure for a substantial distance, means for securing the structure in position, a plastic material covering said supporting structure and embedding the same, the said element also operating to prevent sagging of the plastic material, and tile secured in position over said structure, by the said plastic material.

4. A tile facing for plaster walls comprising an apertured supporting and reinforcing structure disposed adjacent the surface of a wall and in spaced relation thereto, means for securing the structure in position, a plastic material applied to the wall over said structure and embedding the latter, means carried by the reinforcing structure, projecting from, extending for a substantial distance along the rear face thereof and substantially filling the space between said reinforcing structure

and the proximate face of the wall and operating to maintain the plastic material from settling down behind the said supporting and reinforcing structure, and tile secured in position by said plastic material and over the said supporting and reinforcing structure.

5. A tile facing for plaster walls comprising a section of grille work disposed directly adjacent the face of said wall and in spaced 10 relation thereto, fastening means for securing the grille work in position, plastic material contacting the surface of the wall and embedding said grill work, and tiles secured in position by said plastic material and covering 15 said grille work, said grille work embodying rods extending across the rear face of the grill work and arranged in intersecting planes, some of said rods being of greater diameter than others of the rods and abutting 20 the wall surface to hold the remaining portion of the grille work spaced from the wall, the said rods of larger diameter extending across the space between adjacent studs of the structure to which the tile is to be secured, for 25 reinforcing and preventing bulging of the grille work adjacent said space and for supporting the plastic structure.

In testimony whereof I have signed my name to this specification, on this 6th day of 30 November, A. D. 1931.

HENRY BARTELS.
